Rebstock & Reimel,
Automatic Fan,
Nº 17,517. Patented June 9, 1857.

Fig. 1.

Fig. 2.

UNITED STATES PATENT OFFICE.

L. REBSTOCK AND N. REIMEL, OF PHILADELPHIA, PENNSYLVANIA.

AUTOMATIC FAN.

Specification of Letters Patent No. 17,517, dated June 9, 1857.

To all whom it may concern:

Be it known that we, LAWRENCE REB-
STOCK and NICHOLAS REIMEL, of Philadel-
phia, in the county of Philadelphia and
5 State of Pennsylvania, have invented a new
and Improved Ventilating-Fan; and we do
hereby declare that the following is a full,
clear, and exact description of the same,
reference being had to the accompanying
10 drawings, making a part of this specifica-
tion, in which—

Figure 1 is an elevation of my improve-
ment. Fig. 2 is a plan or top view of the
same.

15 Similar letters of reference indicate cor-
responding parts in the two figures.

This invention consists of a new article of
manufacture, viz., a ventilating fan, made
as hereinafter set forth.

20 To enable those skilled in the art to fully
understand and construct my invention, I
will proceed to describe it.

A represents the base of the implement,
which may be constructed of wood or other
25 material, and of circular form. This base
is placed upon casters (a) of the usual con-
struction. On the upper surface of the
base, near its edge, an annular groove, B,
is made, and C is a circular platform sup-
20 ported by two pedestals, (b) (b), and two
hollow uprights, D, D, the uprights passing
through the platform and extending up-
ward a suitable distance. The lower ends
of the pedestals, (b) (b), and uprights, D,
35 D, are provided with rollers or casters (c)
the peripheries of which are fitted in the
groove, B. The under side of the platform,
C, has a pendent rod, E, attached to it; the
lower end of said rod being placed or
40 fitted in a step (d) at the center of the base,
A. The platform, therefore, with its
pedestals and uprights, may be rotated or
turned upon the base, A, the above parts
being secured upon the base by the pendent
45 rod, E, and the rollers or casters (c) which
fit or work in the groove, B.

F, F, represent two uprights, attached to
the platform, C, and G is a fan, the shaft
(e) of which works in bearings in the
50 upper ends of the uprights, F, F. The
shaft (e) has three or more radial rings (f)
attached to it; and a pinion (g) is placed
on each end of the fan shaft (e). H, H',
are two toothed wheels, the axes (h) (h) of
55 which pass transversely through the upper
ends of the uprights, D, D, one through

each, and a drum (i) is placed on each axis
(h); the drums being within the uprights,
and having cords (j) and weights (k) at-
tached to them; see dotted lines in Fig. 1. 60

The wheels, H, H', gear into the pinions
(g) (g) on the fan shaft (e), and the
wheels H, H', are placed loosely on their
axes, and connected with them, when they
are turned in one direction and rotate the
65 fan G, by pawls (l) and ratchets (m); the
axes being disconnected from the wheels
when turned in the opposite direction; so
that the cords (j) may be wound upon the
drums without operating the fan and 70
wheels. The ends of the axes (h) are made
square to receive a key for winding up the
weights.

The wheel, H', gears into a pinion (n)
on a shaft (o) the ends of which are fitted
in pendants, (p), at the ends of a bar (q)
attached to the upper end of one of the up-
rights, F. The outer end of the shaft (o)
has a scape wheel (r) upon it, and (s) is a
75 pallet which works into the scape wheel 80
(r); the pallet being connected with a
pendulum (s') by a crutch (t); these parts
being arranged precisely similar to those
in an ordinary clock.

When the cords (j) are wound upon the 85
drums (i) the fan G will be rotated by the
gearing or clock movement described, and
a blast of air will of course be produced by
the rotation of the fan. By turning the
platform, C, on the base, A, the fan G may
90 be placed in any relative position with the
person receiving the blast, so that the person
may receive the blast more or less direct,
and consequently of a greater or less
strength, as desired.

The above implement being on casters
may be readily moved from place to place.
It may be placed at the bed-side, and kept
in operation during the night, or it may be
placed near a reading or dining table, or by 100
an escritoire, to fan the persons sitting at
such articles of furniture. The device is
very compact, and when not used as a venti-
lator, the platform, C, may serve as a sewing
105 or work table, and may, if desired, be
provided with drawers.

I do not claim, broadly, the driving of
revolving fans by clockwork, as such con-
trivances have long been known and used.
Neither do I claim, broadly, the revolving
110 of mechanism around a given axis, by plac-
ing the mechanism upon movable frames.

The rotating domes of observatories, telescope stands, and other species of mechanism are examples of this kind. But to the best of my knowledge and belief, there never 5 has been made a fan driven by clockwork and arranged as herein shown, so as to be capable of being readily turned upon an axis without moving the whole apparatus. The current of air is thus readily directed 10 toward any given point in an apartment. My invention therefore constitutes a new and useful article of manufacture. No ap-

paratus like it has ever before been known or used. Therefore,

I claim and desire to secure by Letters 10 Patent, as a new article of manufacture—

A ventilating fan, constructed as herein set forth.

LAWRENCE REBSTOCK.
NICHOLAS REIMEI.
